[57] CLAIM

The ornamental design for a disc player, as shown and described.

DESCRIPTION

FIG. 1 is a perspective view of a disc player showing my new design;

FIG. 2 is a top plan view thereof;

FIG. 3 is a left side elevational view thereof, the right side elevational view being a mirror image;

FIG. 4 is a front elevational view thereof;

FIG. 5 is a bottom plan view thereof;

FIG. 6 is a rear elevational view thereof;

FIG. 7 is a front elevational view of a second embodiment of a disc player showing my new design, wherein, in the second embodiment, the center lid portion of the first embodiment shown in FIG. 1 is moved upward; and.

FIG. 8 is a perspective view thereof, wherein the cover portion is in the open position, the portion shown in broken lines is for illustrative purposes only and forms no part of claimed design.
